COAT RACK FOR CHAIRS

Emery Gonczy, Bronx, N. Y.

Application May 4, 1940, Serial No. 333,261

2 Claims. (Cl. 155—190)

This invention relates to new and useful improvements in a coat rack for chairs.

More specifically, the invention proposes a coat rack adapted to be mounted in a chair back and provided with a coat support member adapted to be extended upwards from the top of the chair back when in use.

More specifically, the invention contemplates characterizing the coat rack by a longitudinal casing adapted to be mounted within the material of the chair back and provided with a projecting stem and a latching mechanism for holding the stem in various extended positions. It is proposed that a coat support member be mounted on the top of the stem. It is proposed that the latching means be characterized by a depressible button on one side of a portion of the chair back, this button to be depressible to release the stem.

Still further the invention proposes a modified arrangement in which the stem is provided with an upper section capable of leaning forwards over the chair so that an extra heavy coat supported on the coat rack will not tip the chair backwards.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a chair provided with a coat rack constructed in accordance with this invention, and illustrated with the coat rack extended.

Fig. 2 is a perspective view of the chair shown in Fig. 1 with the coat rack retracted.

Fig. 3 is a fragmentary rear elevational view of Fig. 1.

Fig. 4 is a fragmentary enlarged transverse vertical sectional view of a portion of the chair back shown in Fig. 3.

Fig. 5 is a vertical sectional view taken on the line 5—5 of Fig. 4.

Fig. 6 is a horizontal sectional view taken on the line 6—6 of Fig. 4.

Fig. 7 is a horizontal sectional view taken on the line 7—7 of Fig. 4.

Fig. 8 is a horizontal sectional view taken on the line 8—8 of Fig. 4.

Fig. 9 is a side elevational view of a chair provided with a coat rack constructed in accordance with a modification of this invention.

Fig. 10 is a fragmentary rear elevational view of Fig. 9.

Fig. 11 is a fragmentary enlarged vertical sectional view taken on the line 11—11 of Fig. 10.

The coat rack for chairs, in accordance with this invention, includes a longitudinal casing 10 for vertical engagement in a chair back. Specifically, this casing 10 is mounted within the central vertical section 11^{aa} of a chair back 11^a of a chair 11. The central section 11^{aa} may be suitably hollowed out, and the casing 10 set therein. A stem 12 is slidably mounted in the casing 10 and extends upwards therefrom and through an opening 13 in the top of the chair back 11. A coat support member 14 is mounted on the top of the stem 12, and means is provided for latching the stem 12 in several raised positions.

The casing 10 is formed from sheet metal bent substantially into tubular form. More specifically, the casing 10 has a rear wall 10^a which continues at one side into a side wall 10^b continuing into a narrow front wall 10^c. The back wall 10^a continues from the other side into a side wall 10^d which continues into a narrow front wall portion 10^e continuing into a central partition wall 10^f.

The stem 12 is slidably supported in the compass 10^g bounded by the walls 10^d, 10^e, 10^f and 10^a. This space 10^g is to the left of the partition 10^f. Another space 10^h within the casing 10 is to the right of the partition wall 10^f. The wall 10^f extends from the bottom of the casing 10 to a point 10^{ff} which is some distance down from the top of the casing 10 (see Fig. 4). The top edge of the wall 10^f is slightly bent laterally as shown in Fig. 4.

The means for latching the stem 12 in several raised positions includes a lever 14' which is pivotally supported intermediate of its ends by a pin 15 mounted on a bracket 16 which is supported on the casing wall 10^b. This bracket 16 comprises a sheet metal piece, bent to have a pair of parallel arms 16^a. The lever 14' passes between these arms 16^a and the pintle 15 is supported on these arms 16^a and extends through the lever 14'.

The top end of the lever 14' has a projecting portion 14^a engaging one of a series of ratchet teeth 18 formed upon one side of the stem 12. When the stem 12 is moved upwards or downwards, the projecting portion 14^a may be engaged with another of the ratchet teeth 18. An expansion spring 19 urges the top end of the lever 14' against the ratchet teeth 18. This spring 19 is supported by a pin 20 which is

mounted on the wall 10^b and which extends into an opening 21 formed in the lever $14'$.

A rod 22 is mounted on the bottom end of the lever $14'$ and extends through aligned openings 23 formed in the wall 10^b and in the material of the chair portion 11^a . A handle 25 is mounted upon the outer end of the rod 22 . When the handle 25 is pressed inwards, the lever $14'$ will be pivoted to disengage the projecting portion 14^a from the ratchet teeth.

The coat support 14 comprises a curved bar which is mounted on top of the stem 12 and which is of a shape to conform with and engage the top of the chair back 11^a when the rack is in its collapsed condition. When the stem 12 is in its extended position, as illustrated in Fig. 1, the coat rack is ready to be used. A coat or other garment may be mounted on the coat rack by engaging the shoulders on the coat support member 14 . When the coat rack is not in use the stem 12 and the coat support member 14 are lowered. This may be accomplished by pressing the handle 25 inwards to free the projecting portion 14^a from the ratchet teeth 18 .

In Figs. 9-11 inclusive, a modified form of the invention has been disclosed, which distinguishes from the prior form in the arrangement of the stem $12'$. In accordance with this form of the invention the bottom end of the stem $12'$ is pivotally connected by a pintle 28 with the top end of a member 29 which slidably engages in the casing 10 . The member 29 is in the nature of a bottom extension for the stem $12'$. The stem $12'$ is adapted to pivot forwards in its raised position. It is provided with a shoulder 12^a near its pivot cooperative with a shoulder 29^a on the top of the member 29 , to limit the forward pivoting of the stem $12'$. One side of the member 29 is formed with ratchet teeth 18^a comprising continuations of the ratchet teeth 18 on the stem $12'$. In other respects this form of the invention is similar to the previous form and like parts may be identified by like reference numerals.

When the stem $12'$ is fully extended it may be tilted forwards as illustrated in Figs. 9 and 11. A coat now supported on the rack will lean forwards relative to the chair back so as to prevent the chair from falling backwards.

The chair 11 is constructed with front legs 11^c

and back legs 11^d . The back legs 11^d are set materially rearwards of the chair back 11^a . This is accomplished by continuing the back legs 11^d upwards, and then forwards, and then continuing the same into the chair back 11^a as illustrated on the drawing. The rearwards setting of the rear legs 11^d assists in preventing the chair when carrying a heavy coat from tipping rearwards.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A coat rack for chairs, comprising a vertical casing in a chair back, a stem slidably mounted in said casing and extending from the top edge of said chair back, means for latching said stem in several raised positions, and a coat support member mounted on the top of said stem, said casing being formed from sheet metal material, and having a back wall which at its sides continue into side walls which continue into front walls, and one of said front walls continuing into a rearward extending partition portion.
2. A coat rack for chairs, comprising a vertical casing in a chair back, a stem slidably mounted in said casing and extending from the top edge of said chair back, means for latching said stem in several raised positions, and a coat support member mounted on the top of said stem, said casing being formed from sheet metal material, and having a back wall which at its sides continue into side walls which continue into front walls, and one of said front walls continuing into a rearward extending partition portion, said stem being slidably mounted in the compass of said casing to one side of said partition, the compass to the other side of said partition serving to house said latching means, said partition portion being extended only partially to the top of said casing so that said latching means may engage said stem and hold the same raised.

EMERY GONCZY.
